CLAIM

The ornamental design for a head restraint device for travel, as shown and described.

DESCRIPTION

FIG. 1 is a perspective view of a head restraint device for travel, showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawings depict elements of the head restraint device for travel that form no part of the claimed design. All broken lines form no part of the claim.

1 Claim, 5 Drawing Sheets
